[57] CLAIM

The ornamental design for a key chain box, as shown and described.

DESCRIPTION

FIG. 1 is a top, left perspective view of a key chain box showing my new design;
 FIG. 2 is a top plan view thereof;
 FIG. 3 is a bottom plan view thereof;
 FIG. 4 is a front elevational view thereof;
 FIG. 5 is a rear elevational view thereof;
 FIG. 6 is a left side elevational view thereof;
 FIG. 7 is a right side elevational view thereof;
 FIG. 8 is a top, left perspective view of an alternate embodiment of FIG. 1, the only difference being acceptance of alternate key chain tabs;
 FIG. 9 is a top plan view of FIG. 8;
 FIG. 10 is a bottom plan view of FIG. 8;
 FIG. 11 is a front elevational view of FIG. 8;
 FIG. 12 is a rear elevational view of FIG. 8;
 FIG. 13 is a left side elevational view of FIG. 8; and,
 FIG. 14 is a right side elevational view of FIG. 8.
 The broken line showing of a chain in the accompanying drawings is for illustrative purposes only and forms no part of the claimed design. Further, the broken line shown the chain tab of FIGS. 8-12 is for illustrative purposes and forms no part of the claimed design for the alternate embodiment.
